C. E. DE LANO

MOTOR VEHICLE MOVER

Filed June 6, 1922

Inventor
C.E. DeLano

By *John Murphy Jr.* Attorney

Patented Jan. 6, 1925.

UNITED STATES PATENT OFFICE.

CHARLES E. DE LANO, OF FOREST CITY, ARKANSAS.

MOTOR-VEHICLE MOVER.

Application filed June 6, 1922. Serial No. 566,279.

To all whom it may concern:

Be it known that I, CHARLES E. DE LANO, a citizen of the United States, residing at Forrest City, in the county of Saint Francis and State of Arkansas, have invented certain new and useful Improvements in Motor-Vehicle Movers; and I do hereby declare the following to be a full, clear, and exact description of the invention, such as will enable others skilled in the art to which it appertains to make and use the same.

The primary intent of the present invention is the provision of means whereby a stalled motor vehicle may be moved by its own motive plant to clear an obstruction or draw itself out of the mud, sand or other place from which it cannot be moved in the ordinary way and which requires the application of great force to clear the obstruction, mud or other condition causing the vehicle to stall.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a diagrammatic view showing the application of the invention,

Figure 2 is an elevation of the drum, and

Figure 3 is a detail plan view of the drum, parts being broken away.

Corresponding and like parts are referred to in the following description and designated in the several views of the drawings by like reference characters.

The device consists of a drum 1 of such size and formation as to fit snugly over the outer end of the hub of a drive wheel of the stalled motor vehicle to be moved. The drum 1 has outer flanges at its ends to stiffen and reinforce the same and to prevent displacement of the cable 2 when wound upon the drum in the operation of the device. Arms 3 radiate from the inner end of the drum and terminate in laterally disposed spoke-engaging hooks 4. The number of arms 3 is immaterial so long as they subserve to make positive and firm engage-

ment of the drum 1 with the drive wheel of the motor vehicle. In practice, the drum with its flanges and the arms and hooks are of integral formation, the same constituting part of a single casting, thereby obviating the formation of joints and resulting in the provision of a substantial, light and efficient device.

The device may be carried as an accessory of a motor vehicle and will be constructed with reference to the drive wheel thereof so as to snugly fit the outer end of the hub and insure the hooks 4 registering with the spokes to be engaged thereby. In the event of a motor vehicle stalling by encountering a soft place in a road, such as mud or sand, or dropping into a rut or depression, or meeting with an obstruction which precludes the vehicle clearing the same in the usual way, it may be moved by fitting the drum 1 to the hub of a drive wheel and engaging the hooks 4 of the arms 3 with certain spokes of said drive wheel. The cable 2 is attached to a stake 5, or other convenient anchoring means, after which the opposite end portion of the cable is engaged with the drum 1 so as to wind thereon when the motor of the vehicle is started, thereby enabling the vehicle to clear the obstruction of whatever character by power derived from its motive plant. After the vehicle has been moved so as to clear the obstruction the drum may be readily disengaged from the drive wheel and may be carried as an adjunct without occupying any appreciable space. It is observed that the drum may be attached and disconnected from the drive wheel without requiring the use of any tool or fastening means other than the hooks 4 which form a part of the device.

To prevent marring the finish of the spokes and hub of the drive wheel it is to be understood that the hooks 4 and drum 1 will be suitably lined with any preferred material as will be readily understood.

What is claimed is:

An attachment of the class described made in a single piece consisting of a drum, the drum being hollow to house the wheel hub and having its wall imperforate throughout, said drum at its outer end being closed and having an outwardly extending cable-retaining flange, that portion of the drum adjacent the flange having a truly cylindrical outer surface, the drum as an inward con-

tinuation of said cylindrical surface being flared, the inner wall of said flange being flat and in a plane at a right angle to the longitudinal axis of the drum, the drum 5 at the side adjacent the wheel having a flange of greater diameter than the first flange and having its outer surface adjacent the margin substantially flat and in a plane parallel to the said plane arms radiating from said drum at its inner end, hooks integral with said arms extending at a right angle thereto and on the opposite side to the drum, said hooks being adapted to en-

gage wheel spokes and all being open at the same side, the hooks being applicable to 15 the wheel spokes by movement circumferentially of the wheel, in combination with a draw element to extend from the drum to a support and to maintain said hooks in engagement with the wheel spokes when in use. 20

In testimony whereof I affix my signature in presence of two witnesses.

CHARLES E. DE LANO.
